UNITED STATES PATENT OFFICE.

HERBERT D. HOUGH, OF CRANSTON, RHODE ISLAND, ASSIGNOR TO WIGHTMAN AND HOUGH COMPANY, OF PROVIDENCE, RHODE ISLAND, A CORPORATION OF RHODE ISLAND.

CIGARETTE CASE

Application filed October 27, 1920. Serial No. 419,801.

To all whom it may concern:

Be it known that I, HERBERT D. HOUGH, a citizen of the United States, and resident of Cranston, in the county of Providence and State of Rhode Island, have invented 5 certain new and useful Improvements in Cigarette Cases, of which the following is a specification.

The invention relates in general to an 10 article for carrying small packages in the pocket and specifically relates to a cigar or cigarette carrying case or, rather to a case which is designed to carry the paper pack- 15 age of cigarettes as they are sold on the market.

One of the objects of the invention is to provide a simple and economically constructed form of case in which separate cigarettes or the paper package of the same 20 can be readily mounted in protected position and from which the individual cigarettes may be withdrawn one at a time as needed.

The invention features a two-part cover 25 hinged together so as to form a closure designed to inclose a package holder hingedly mounted on the hinge connection between the parts of the covers and otherwise fol- 30 lowing in general design similar conven- tional structures now in common use. The present disclosure features an improved 35 form of holder characterized by being formed of a one-piece sheet metal stamping which can be constructed and mounted in place without the necessity of using complicated machinery or other refined mechanical operations which have made present forms of such devices high in manufacturing costs.

40 Another object of the invention is to provide a simple, neat and improved form of spring hinge connection which will simultaneously move the covers into open position and at the same time dispose the holder 45 in a resiliently mounted upright position from which the cigarettes may be conveniently withdrawn without danger of breaking the same.

Still another object of the invention is to 50 provide a form of holder, the upper edge of which is designed to facilitate the tearing of the paper cover or original wrapping from the market package in exposing the contained cigarettes.

Various other objects and advantages of 55 the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawings:—

Figure 1 is a view in side elevation of a preferred embodiment of the invention dis- 60 posed in open position;

Figure 2 is a fragmentary, enlarged view 65 of a part of the showing in Figure 1 and 70 taken in section approximately on the broken line 2—2 of Figure 1 looking in the direction indicated by the arrows; and

Figure 3 is a plan view of the metal blank 75 prior to its being folded into the holder shown in Fig. 1.

In the following description and in the claims, parts will be identified by specific names for convenience of expression but 80 they are intended to be as generic in their application to similar parts as the art will permit.

In the drawings there is shown a pair 85 of dished covers 10 and 11 pivotally connected along adjacent edges by a hinge con- 90 nection 12. This hinge connection includes a plurality of eye forming lugs 13 extending from each of the covers in offset relation and bent back upon themselves to form aligned eyes. The lugs 13 are arranged 95 so that a pair of spaces are exposed so as to permit the mounting of the holder as hereinafter described. A locking rod 14 is passed through the eyes from both the cover and holder to complete the hinge con- 100 nection.

For the purpose of projecting the covers into open position the pivotal connection includes a cover spring wire 15 passed through the eyes of the hinge, one end 16 105 of which bears on the inner side of the cover 10 as shown in full lines in Figure 2 and the opposite end 17 bears on the cover 11 as shown in dotted lines in Figure 2.

The holder is formed from a single sheet 110 of perforated and shaped sheet spring metal more particularly shown in Figure 3. Re- 115 ferring particularly to the detailed showing

of the stamped blank in this figure it is noted that it includes a central bottom portion 18 substantially rectangular in outline from opposite longitudinal edges 19 of which extend side forming extensions 20. Each of the side forming extensions 20 is provided with lateral extensions 21 designed to be folded at right angles to the plane of the side 20 and along the lines 22, 10 so as to form the relatively narrow two part sides 23 of the completed holder shown in Figure 1. Similarly, each of the extensions 20 is bent at right angles to the plane of the bottom 18 and along the edges 19 15 so as to form the wide sides 24 of the completed holder.

The bottom 18 is provided with two oppositely facing E-shaped slots 25 which form lugs 26. These lugs are bent outwardly or 20 downwardly and have their free edges turned back upon themselves to form eyes 27 passed about the locking rod 14 and disposed in the spaces between the lug eyes 13. For the purpose of maintaining the holder 25 in upright position shown in Figure 1, a holder spring rod 28 is passed through the aligned eyes 13 and 27 and bears at its opposite ends 29 and 30 on opposite sides of the upstanding lugs 26 beneath the bottom 30 18.

The upper edges of the holder are provided with a serrated paper cutting edge 31 and the parts are so proportioned that the cigarette package or original wrapper extends 35 above the cutting edge in position to permit a torn portion of the paper to be drawn across the serrated edge. The extensions 20 are provided with stamped out openings 32 which contribute to a light construction 40 without impairing the necessary rigidity of the sides 24.

In operation it will be understood that this case is used in the manner in which similar forms of cigarette cases are used and 45 the opening of the cover is effected by the release of a catch 33 which permits the spring 15 to act on the covers and move the same into the open position shown in Figure 1. At the same time the spring 28 acts 50 upon the holder to displace the same from the covers and position it in the upstanding position shown in Figure 1.

The user will position the individual cigarettes or, preferably, the package of cigarettes in the holder, springing apart the sides 24 if this should be necessary. The resiliency of the metal will cause the sides to spring back into normal position gripping the sides of the contained package.

60 In case of a close fit it is possible for the operator to work the package towards the bottom by engaging the same through the openings 32 in opposite sides of the holder. With the package in position the operator 65 can tear off the paper covering making use

of the serrated edge in detaching the torn parts of the paper package from the main body of the package.

By means of a device of this character it is possible to construct a cigarette or cigarette-package holder by a simple stamping operation and assemble the parts by threading the wires 14, 15 and 28 through the hinge eyes and binding the ends of the wires 15 and 28 as suggested. 70 75

Having thus described my invention, I claim:

1. The combination with a two-part cover and a hinged connection for said cover parts, of a one-piece metal holder fashioned to receive a package of cigarettes or the like in the original wrapper, having walls enclosing such package and split into portions having limited resilient movement relative to each other, and means for pivotally connecting said holder to the said hinge connection to permit said holder to nest in either of said cover sections when in their open position. 80 85 90

2. In a cigarette case, the combination with a pair of hinged covers, of a one-piece metal holder movably connected to the covers to nest in either of the cover sections, said holder comprising oppositely disposed sides having a resilient freedom of movement relative to each other yieldingly to hold a plurality of cigarettes and the wrapper thereof, said side having serrated cutting edges on which to cut the wrapper. 95

3. In a device of the class described, a holder to receive a plurality of cigarettes and the wrapper therefor, comprising oppositely disposed sides having a limited relative movement to each other to hold yieldingly the cigarette package, a bottom portion integrally connecting the sides, a cover for housing the holder, and a pivotal connection between the cover and the holder, to permit said holder to nest in the cover sections when the same are open, said side having serrated cutting edges on which to cut the wrapper. 100 105 110

4. In a device of the class described, a holder to receive a plurality of cigarettes and the wrapper therefor, comprising oppositely disposed sides having a limited relative movement to each other to hold yieldingly the cigarette package, a bottom portion integrally connecting the sides, two pivoted cover sections for housing the holder, and a pivotal connection between the cover and the holder to permit said holder to nest in either of the cover sections whenever the same are open, the holder having a serrated cutting edge on which to cut the wrapper. 115 120 125

5. In a device of the class described, the combination of a pair of covers, a hinged connection therefor including lugs formed integrally with each of the covers and bent 130

- back upon themselves to form aligned eyes, a holder constructed to support a cigarette container and provided with a lug bent back upon itself to form an eye, a locking rod 40
 5 passed through the aligned eyes to complete the hinged connection, thereby to permit said holder to nest in the above sections when the same are open and a spring rod passed through certain of said aligned eyes
 10 and acting on the covers normally to maintain the same in open position.
 6. In a cigarette package containing case, the combination with a pair of covers, of a one-piece metal holder movably connected 45
 15 to the covers and enclosed thereby, said holder comprising oppositely disposed sides fashioned to receive a package of cigarettes in its original wrapping and yieldingly hold said package against displacement and having cutting edges adjacent the upper portion 50
 20 of the cigarette wrapping, lugs integral with the bottom of the holder forming eyes, and means engaging the eyes and the cover to form a pivot therefor and to permit the 55
 25 holder to nest in either of the cover sections when the same are open.
 7. In a device of the class described, the combination with a cover of a one-piece sheet metal package holder including a bottom and oppositely disposed symmetrical sides 60
 30 resiliently connected by means of the bottom so as to have a limited field of relative movement and having their upper edges serrated, lugs formed integrally with the 65
 35 bottom and adapted to constitute part of a means for maintaining the holder in position and a spring bearing on said lugs for
 disposing the holder in relation to the cover, said sides having flanges along at least some of their edges to support a cigarette 40
 package.
 8. In a cigarette package containing case, the combination of a one-piece metal package holder including a bottom and oppositely disposed sides resiliently connected by 45
 the bottom to have a limited field of relative movement, lugs formed integrally with said bottom provided with eyes, a cover comprising two parts for enclosing the holder, each of said cover-parts being provided with an eye, a locking rod engaging the eyes to form a pivot for the cover-parts and the holder, a spring mounted in the eyes and engaging the parts of the cover normally to hold same in a predetermined 50
 position, and a separate spring mounted in said eyes engaging the holder normally to hold the same in a predetermined position relative to the cover.
 9. In a cigarette package containing case 60
 the combination with a cover, a one-piece sheet metal holder housed within said cover, said holder having two oppositely disposed sides integrally connected, said sides having flanges to surround a package of cigarettes 65
 and having serrated edges for use in opening packages held in the holder, said sides being resiliently movable with respect to one another.
 Signed at New York in the county of New 70
 York and State of New York this 14th day
 of October A. D. 1920.
